 Boaler, Spondon, near Derby, England, assign-
 ors to Celanese Corporation of America, a cor-
 poration of Delaware

Application February 9, 1934, Serial No. 710,434
 In Great Britain February 20, 1933

5 Claims. (Cl. 66—8)

This invention relates to knitting machines and is an improvement in or modification of the invention described in U. S. application Serial No. 446,276 filed 22nd April, 1930.

5 U. S. application Serial No. 446,276 describes a knitted fabric and a method and a machine for knitting the same, the fabric being a tubular fabric in which the loops or stitches form close and continuous helical courses about the fabric, 10 while the warp threads of which the fabric is composed all traverse open helical paths about the fabric. In order to knit this fabric, a machine is employed which comprises an endless series of needles adapted to be operated successively by needle cams, and one or more series 15 of guides, each series of guides comprising approximately one guide for each needle, and each guide being operated to pass its thread round the needles prior to knitting by means of cam rings moving with the knitting cams. The guide series move slowly either in the same direction as the knitting cams or in the opposite direction and have a slightly greater or a slightly less 20 number of guides than there are needles according to whether they are travelling in the same or in the opposite direction to the knitting cams. Each series of warps is fed in sheet form from a source of supply to the guides and thence to the needles. The invention is particularly concerned 25 with a machine of this type in which two series of guides are provided.

According to the present invention two series of warp threads are fed to a circle of needles by means of two concentric rings of guides and both series of warp threads pass between the 30 rings of guides on their way to the needles.

The present invention enables the warp threads to be fed directly to their guides and thence to the needles without passing by any of 35 the guide operating mechanism, and without having to be deflected into a devious path in order not to contact with such mechanism. By reason of their more direct path, the tension imparted to the threads may be reduced, and in addition, 40 the two sheets of warps may follow substantially similar paths, so that tensioning conditions are equal as between the sheets, as well as between the threads in each sheet. The guides are enabled to operate by movements substantially at 45 right angles to the direction from which the yarns come to them, so that the movements of the guides themselves have no substantial effect on the tension in the threads.

Furthermore, a clear view is permitted of the 50 warp threads and the fabric produced therefrom,

and of the working parts of the machine. Thus, the replacement of guides or needles when necessary, is greatly facilitated, and the manipulation of the warp threads, whether in the operation of threading them initially through the guides 5 and passing them to the needles, or in any attention they may need during knitting, is made easier.

Where sinkers are employed, as is usual in machines employing bearded or spring needles, these 10 elements engage the thread proceeding from each needle to the guide which has wrapped the thread round that needle, and makes a loop of thread which is subsequently taken up by the needle when it descends to knit a further loop in the 15 fabric. In order to ensure adequate engagement of the sinkers with the threads, the thread guides in the present invention may be given a sliding motion which has not only a radial component, 20 carrying the guides across the line of the needles, but also a circumferential component. A convenient way in which such a motion may be effected is by mounting the guides in tricks cut in guide rings, the tricks being cut, not radially, but at an angle to the radial, so that, in sliding in such 25 tricks, the guides have a circumferential as well as a radial motion. By virtue of the circumferential motion, the guides may pass over the spaces between needles so as to guide their threads through such spaces, and still carry the threads 30 fairly across the paths of the sinkers, which move radially through the between-needle spaces. The 35 sense of the angle at which the tricks are cut is such that the inward movement of each guide has a component in the direction of general rotation of the guide. In this manner, while each thread is drawn further in the direction of rotation of the guides than would otherwise be the case, and is led fairly across the path of a sinker, the additional movement is taken back again 40 when the guides move outwardly to wrap each thread round a further needle.

It will be understood that, as in U. S. application Serial No. 446,276 the several motions between the needle assembly, the needle and guide 45 cam assembly and the two guide assemblies are only relative motions and any one of these assemblies may be maintained stationary while the rest rotate at the requisite speed and in the requisite direction to produce the desired relative motions. In the present invention it is generally preferable to maintain one of the sheets of warp threads stationary, while the needles, the needle cams and the other set of warp threads rotate at different speeds. Where a circular series of ver- 50

tical needles is employed, and where as is convenient the warp threads pass downwardly to the heads of such needles, it is preferred that the outer sheet of warp threads should be maintained 5 stationary in the manner indicated above, while the inner sheet is caused to rotate.

By way of example a form of knitting machine according to the invention will now be described in greater detail with reference to the accompanying drawings in which:—

Figure 1 is a sectional view of one half of a machine according to the invention, and

Figures 2, 3, 4 and 5 illustrate details of the machine shown in Figure 1.

15 The machine comprises a stationary frame having a base 11 on which are mounted columns 12 supporting a stationary ring 13. The ring 13 in turn carries columns 14 which carry a further stationary ring 15. Rotatably mounted upon the 20 ring 13 is a ring 16 carrying the needle cylinder 17, the ring 16 being driven by a worm gear 18 mounted on a shaft 23 carried in a bracket 20 on the under side of the ring 13. The other end of the shaft 23 carries a worm gear 21 engaging with a worm 22 mounted upon a shaft 19. The shaft 19 is driven by bevel gears 24, 25 from the driving shaft 26 of the machine, and is supported and held in position by means of bearings 28 carried by the stationary rings 13, 15.

25 30 Needles 29 and presser jacks 30 are carried in tricks in the needle cylinder 17, and secured outside the needle cylinder 17 is a sinker ring 31 carrying sinkers 32 in radial slots. Needle cams 33, and sinker cams 34 connected to said needle cams by means of brackets 35 are driven by means of a gear 36 from the main shaft 19 of the machine.

35 40 At the upper end of the machine the ring 15 carries brackets 38 on which are mounted warp beams 39. Rotatably mounted on the ring 15 is a ring or spider 40 carrying brackets 41 in which are mounted a second set of warp beams 42. In connection with each set of beams is a pair of rollers 43, 44, the upper roller 43 being made of steel, while the lower roller is of rubber or like 45 soft material. The warp threads 45, 46 coming from the beams 39, 42 are fed by means of the rollers 43, 44, a fine adjustment of the rate of feed of the threads being permitted by the adjustment of the pressure between the steel rollers 43 and the soft rollers 44, pressure screws 47 being 50 provided for this adjustment.

45 55 Below and inside the stationary ring 15 is a further stationary ring 48 carried from the ring 15 by means of brackets 49. A further ring 50 is rotatably mounted on the stationary ring 48, its edge being geared at 51 to enable it to be driven from a worm 52 by means similar to the means 18, 19, 21, 22 previously described. These driving means are omitted for the sake of clarity.

60 65 70 The inner guide ring 53, is suspended from the rotating ring 50, by means of brackets 54, the ring 50 being in the form of a spider, and being connected to the upper rotating ring or spider 40 by means of a short shaft 55. In this manner the ring 40 together with the beams 42 mounted thereon, and the inner guide ring 53 together with guides 56 sliding in tricks therein, rotate as a system driven by the worm 52 on the shaft 19. Over the inner guide ring 53 is a cam ring 57 acting 75 upon the butts 58 of the guides 56. The cam ring is driven by means of a shaft 59 carried in bearings 60, 61, and provided with gears 62, 63. The lower gear 62 engages with the inner edge of the cam ring 57, while the upper gear 63 engages with an intermediate driving ring 64 rotatably

mounted over the ring 50. The intermediate ring 64 is driven at relatively high speed by means of a gear 65 on the shaft 19.

5 The outer guide ring 66, similar in section to the inner guide ring, is carried by brackets 67 on the columns 14 of the machine. The cam ring 68, which acts upon the butts 69 of the guides 70, is driven by means of a gear 71 on the shaft 19.

10 A worm gear 72 is provided upon the shaft 59 driving the lower guide ring 53, the worm 72 engaging and driving a worm gear 73 mounted in conjunction with a sprocket 74. The sprocket 74 is connected by means of a chain 75 to a sprocket 76 driving the rollers 43, 44 and the inner set of beams 42. The outer set of beams is driven by means of a chain 77 in a similar manner from the shaft (not shown) lying between and connecting the gears 51, 52.

15 20 Figure 2 shows details of the arrangement of guides, needles and associated parts and the guide ring supports. As previously stated, the outer guide ring 66 is carried by means of brackets 67 on the columns 14, while the inner guide ring 53 is carried from the rotating ring 50 by means of brackets 54. The brackets 54 also carry the 25 bearings 69, 61 for the shaft 59, the bearings being held upon supporting straps 78 extending between two brackets 54 as shown in Figure 3.

25 30 The sinker ring 31 is carried by the needle cylinder 17, an annular ridge or shoulder 79 being provided on which the sinker ring 31 rests. The sinker ring 31 is prevented from rotating relatively to the needle cylinder 17 by means of a set screw 80 extending right through the sinker ring. Springs 81, 82 are provided for holding 35 in position the needles 29 and the presser jacks 30 respectively. The contours of the needle cylinder are clearly shown in this figure. It will be understood that the tricks into which the needles 29 and presser jacks 30 fit extend right through 40 the sinker support ridge 79 and into the surface of the cylinder.

35 40 45 The threads 45 coming from the outer warp beams 39 are guided by means of a ring 83 carried by the brackets 49 and are thereby caused to proceed substantially vertically to the heads of the outer guides 70. The threads 46 coming from the inner beams 42 pass over the guide ring 84 carried on the intermediate driving ring 64, which guide ring causes them to clear the teeth on the 50 inner side of the ring 64. The threads 46 are then guided over the inner surface of the slowly rotating ring 50 to the heads of the inner guides 56. Since the paths of the threads 45, 46 to the guides 70, 56 are substantially vertical, and since 55 the motions of the guides 70, 56 are horizontal, the motions of the guides do not affect the tensioning of the threads. Proceeding from the guides 70, 56 the threads 45, 46 are knitted into fabric 85 which passes to a take-up device 86 60 driven from a geared ring 87 under the base plate of the machine. The ring 87 is driven by means of a gear 88 on the shaft 19.

65 70 75 In Figure 4 the arrangement of the guides and guide tricks in the guide ring 53, 66 is shown. The profiles of the guide cams are shown in dotted line at 91, 92 and the guides are shown as being actuated in accordance with these cam profiles. The tricks 93, 94 in which the guides are caused to slide are inclined to the radial in such a manner that when moving inwardly, the ends of the guides have a motion with a circumferential component as well as a radial component, so that they move further in the direction in which they are rotating. On the sides of the figure the 75

guides are omitted to show the sinkers and needle heads beneath. The direction of the threads as they are led from the needles 29 to the heads of the guides is shown more clearly in the enlarged view of Figure 5 which includes the threads 95, 96. It will be seen that the inclination of the guide tricks to the radial causes the threads to be moved more fairly across the path of the sinkers 32 than would otherwise be the case, the end 10 of each guide (indicated by a dot in Figure 5) terminating its movement behind a needle, despite the fact that the guide has moved through the space between two needles. The lines of travel 15 of the guides, that is to say, the lines of the tricks in which they slide, are shown dotted at 97, 98. It will be understood that in Figures 4 and 5, the view shown of the sinkers is a horizontal section through the throats of the sinkers, this being the relevant part of the sinker in connection with the sinking of loops prior to knitting. The full shape of the sinker is clearly 20 shown in Figures 1 and 2.

What we claim and desire to secure by Letters Patent is:—

- 25 1. In a circular warp knitting machine, a circle of needles, a circle of sinkers adapted to move radially between said needles, guides for controlling warp threads knitted by said needles, and means for imparting to each of said guides a motion across the circle of needles, such motion being inclined to the radial motion of a sinker so as to lead a thread from a needle across the path of such sinker.
- 30 2. In a circular warp knitting machine, a circle of needles, a circle of sinkers adapted to move radially between said needles, two concentric guide rings, one outside and one inside said circle of needles, two sets of guides for leading two sets of warp threads to the heads of said needles, said guides being slidably mounted in said guide rings, and said guide rings having, for the reception of

said guides, tricks cut at an angle to the radial, so that each guide, in sliding, leads a warp thread from a needle across the path of a sinker.

3. In a circular warp knitting machine, a circle of needles, a circle of sinkers adapted to move radially between said needles, two concentric guide rings, one inside and one outside said circle of needles, guides slidably mounted in said guide rings for guiding two sets of warp threads to the heads of said needles, cams for actuating said guides to slide in said guide rings, said rings having tricks for the reception of said guides, which tricks are cut at an angle to the radial so that each guide in sliding leads a thread from a needle across the path of a sinker, and means for leading each set of warp threads between said guide rings to the guides in a direction perpendicular to the direction of sliding of the guides. 15

4. In a circular warp knitting machine, a circle of needles, a circle of sinkers adapted to move radially between said needles, two sets of guides adapted to lead two sets of warp threads to the heads of said needles, two substantially concentric guide rings, one outside and the other inside the needle heads, said guide rings having tricks 20 cut at an angle to the radial in order to carry said guides, means for imparting continued relative circular motions between said guide rings and said circle of needles, and means for leading both sets of warp threads between said rings to the 25 guides in a direction substantially perpendicular to the direction of sliding of the guides.

5. A circular warp knitting machine provided with mechanism according to claim 4, wherein means are provided for driving the needles and 30 the inner guide ring, and wherein the outer guide ring is maintained stationary.
